UNITED STATES PATENT OFFICE

HARRY S. MONTGOMERY, OF OIL CITY, PENNSYLVANIA

CORD REEL

Application filed January 9, 1929. Serial No. 331,290.

This invention relates to cord reels and more particularly to that type of reel on which cord is stacked for use in tying up packages.

5 In confectionery shops and like places where a large number of small packages are dispensed by sales ladies, it is very desirable to have a cord reel which will play out the cord as it is desired for tying packages, but 10 at the same time not produce a "drag", that is, to permit of the easy unwinding of the cord and yet not permit it to unwind with such ease that an excess of unwound cord will be present. Such an excess of unwound cord is 15 untidy, in the way of wrapping packages, often requires the stooping over of the sales ladies to reach a dropped end thereof, and generally effects a lack of economy.

To remedy this defect it has been customary 20 to produce a braking effect upon the reel, as by springs or other positive braking devices. As a result of these braking devices on the reel, a "drag" is produced. It is not easy to provide a reel of sufficient ease of 25 winding and at the same time avoid this "drag". The effect of the "drag" is to cause the operator to yank at the cord with the result that an excess of unwound cord is produced.

30 The object of my invention is to avoid these difficulties. To that end the reel of this invention seeks to permit of the easy unwinding of the cord and at the same time produce a slight braking effect, yet enough to accomplish the braking without inducing the sales ladies to yank at the cord.

A further object of the invention is to simplify the devices now on the market for this purpose.

40 Another object of the invention is to produce a bearing in which this braking effect is provided without the use of springs and in which the braking effect will automatically adjust itself.

45 Other objects and advantages of the invention will hereinafter appear in the following description and the novel features thereof will be particularly pointed out in the appended claims.

50 Like letters of reference indicate like parts

throughout the several figures of the drawings in which

Figure 1 is a sectional view through the reel,

55 Figure 2 is a similar view on a slightly enlarged scale of one bearing,

Figure 3 is an elevation of one reel support, and

60 Figure 4 is a view showing a slightly modified form of reel construction.

The numeral 10 indicates a spool of cord comprising a shank 11 with flanges 12 and 13 which may be made of stout cardboard attached to the wooden shank 12 by screws 14. These screws also serve the purpose of attaching a metal end 15 to the shank 11, a suitable spacing disc 16 being inserted between the metal end and the flange. Projecting from the metal ends are the stub shafts 17.

65 The reel just described is a construction wellknown. It is supported in standards 18 which are provided with bases 19 adapted to be fastened by any suitable means to a base or floor.

70 The upper end of the standard is provided with a kerf 20, the base of which is curved to form a bearing 21 for the stub shaft 17. To either side of the bearing 21 are cut grooves 22 opening into said bearing. The kerf end of the grooves, it will be appreciated, 75 extend through the width of the standard. In the grooves 22 are inserted felt 23 in pencil form, and in the kerf 20 above the bearing 21 is a felt block 24. Between the spool end 15 and the standard there is mounted on the stub shaft a metal washer 25. By the term "felt" 80 as herein used is meant any material having the qualities and capable of the functions of felt as it is employed in the combination herein described and claimed.

85 The felt pencils are inserted in the grooves 22 in such a way that they slightly project into the bearing opening 21. The stub shaft having the metal washers 25 thereon are inserted in the kerf 20 and permitted to occupy 90 the bearing openings 21. The felt block 24 is then inserted in the kerf and pressed down upon the stub shaft. The bearing thus formed for the stub shaft consists of the metal 95 lower portion of the kerf, the projecting felt 100

of the pencils, and the lower portion of the 5
felt block. It will be appreciated that the
felt pencils and block, while retaining the
stub shaft in position in the standard, at the
same time produce a braking effect and this
braking effect is controllable or adjustable
through a variety of expedients which will be
described. But it is designed to produce just
enough braking effect to prevent unaided un-
winding of the spool reel and yet permit of
an ease of unwinding which will not tempt
the user of the reel to yank at the cord.

In assembling the spool in the standards
it is designed that the felt element of the bearing
15 shall be put in place with sufficient force
to cause a substantial braking on the reel.

But it will be also appreciated that when
the reel is turned for the first time any ex-
cess of braking effect will be relieved after
20 the first turning as it will cause a re-setting
of the felt to a position where it may be said
to be adjusted to accommodate itself to the
requisite braking effect. If at any time this
braking effect is released for any reason to a
25 point where unwound cord is present in the
normal operation of the reel it is only neces-
sary to make one or more of several adjust-
ments of the felt.

A pressure downward on the felt block 24
30 will cause the felt block to more firmly engage
the stub shaft and this may be sufficient to re-
produce the braking effect. Or the pencils of
felt may be rotated within the grooves 22 to
bring a new surface against the stub shaft
35 and this expedient may be employed to re-
produce the braking effect. Or it may only
be necessary to take a lead pencil or similar
blunt pointed instrument and press in on the
felt pencils toward the spool, and this will
40 have the effect of compressing the felt to a
new braking facility. Or it may be that new
felt pencils, after long use of the reel, might
be desirable. They are readily inserted in the
grooves 22. And likewise a new felt block
45 might be inserted or the present block turned
upside down, or the present block trimmed
with a pair of shears to produce a new surface
of contact with the stub shaft. Nor does this
exhaust the possibilities for it will be appreci-
50 ated that if either the pencils of felt or the
block of felt were pressed inwardly toward
the spool, the inner surfaces thereof would
bear against the metal washers 25 so as to
press it into contact with the metal end of the
55 spool and thereby produce a braking effect.

In Figure 4 is shown a slightly modified
form of spool in which the wooden shank 26
has a bore 27 therein into which are inserted
the shaft sections 28 and 29, these sections
60 being screwed together as shown at 30. The
metal flanges 31 have on their inner faces pro-
jections 32 which take into pockets or recesses
in the ends of the shank 26 in order to secure
a rotation of the shank with the flanges 31. In
65 this form the remaining parts are similar to

those shown in Figure 1 and a detailed de-
scription thereof will not be necessary. It
will be appreciated that the simple screwing
together of the sections of the shaft will
secure the parts of the spool in position.

It will be obvious that by the construction
of parts described herein, a reel is produced
which can be easily assembled and wherein
the spool can be readily inserted in its sup-
porting standards and removed therefrom,
70 and one in which there is produced a novel
bearing combining the several capabilities of
a screw holding the spool in place and pro-
ducing a braking effect which might be said
to be automatically adjustable in order to pre-
80 vent the presence of "drag" and yet be suf-
ficiently strong to prevent the presence of un-
wound cord.

What is claimed is:

1. In a bearing for a cord reel, a support 85
for a shaft end having a bearing opening
therein, a recess or pocket adjacent said
opening and communicating therewith, and
a felt filling for said pocket projecting into
90 the bearing opening to produce a braking
effect on the shaft in said opening.

2. In a bearing for a cord reel, a support-
ing standard, a kerf in said supporting stand-
ard at the bottom of which a bearing opening
95 is provided, a shaft insertable in said bearing
opening through said kerf, and a block of felt
filling said kerf and bearing upon said shaft
to produce a braking effect.

3. In a bearing for a cord spool, a stand-
ard, a bearing opening in said standard, a 100
shaft in said opening, a pocket encircling a
portion of said bearing opening, and a felt
filling for said pocket designed to produce a
braking effect upon the shaft in said opening.

4. The combination of claim 3 in which 105
the pocket containing the felt extends to the
outside of the bearing, whereby manual pres-
sure may be exerted upon the felt filling in
order to increase the braking effect.

5. The combination of claim 3 in which the 110
pocket containing the felt extends across the
standard, whereby manual pressure may be
exerted upon the felt filling in order to in-
crease the braking effect upon the spool body.

6. The combination of claim 3 in which a 115
spacing washer is provided between the stand-
ard and the spool, and the pocket containing
the felt extends across the standard, where-
by manual pressure may be exerted upon the
felt filling in order to increase the braking 120
effect upon the shaft end and upon the spool
body.

In testimony whereof I affix my signature.
HARRY S. MONTGOMERY.
